DESIGN FOR A TEXTILE FABRIC OR SIMILAR ARTICLE

Paul Reiman, New York, N. Y., assignor to
Goldstein-Wilkins Corporation, New York,
N. Y.

Application December 16, 1933. Serial No. 50,091

Term of patent 3½ years

To all whom it may concern:

Be it known that I, PAUL REIMAN, a citizen of Germany, residing at 251 West 71 Street, New York, New York, have invented a new, original, and ornamental Design for a Textile Fabric or Similar Article, of which the following is a specification, reference being had to the accompanying drawing, forming a part thereof.

The figure is a plan view of a textile fabric showing the complete width of the fabric to which my new design is applied, except for the portion, between the break lines at A, which is

similar to that on either side thereof. The dot and dash lines on the drawing outline substantially the design unit, which unit is repeated in regular succession as indicated by the extensions beyond the unit boundaries.

I claim:

The ornamental design for a textile fabric or similar article as shown and described.

In testimony whereof I have signed this specification.

PAUL REIMAN.
